CLAIM

The ornamental design for a laundry detergent dispenser, as shown and described.

DESCRIPTION

FIG. 1 is a top perspective view of a laundry detergent dispenser, showing my new design;

FIG. 2 is a bottom perspective view thereof;

FIG. 3 is a bottom perspective view of the laundry detergent dispenser in another angle;

FIG. 4 is a front elevational view thereof, the rear elevational view being a mirror image of FIG. 4;

FIG. 5 is a left side view thereof;

FIG. 6 is a right side view thereof;

FIG. 7 is a top plan view thereof; and,

FIG. 8 is a bottom plan view thereof.

The broken lines in the figures are for the purposes of illustrating portions of the laundry detergent dispenser, which form no part of the claimed design.
